UNITED STATES PATENT OFFICE.

CHARLES WAGNER, OF NEW YORK, N. Y.

MACHINE FOR COVERING LITHOGRAPHIC-PRINTING ROLLERS.

SPECIFICATION forming part of Letters Patent No. 734,381, dated July 21, 1903.

Application filed July 28, 1902. Serial No. 117,312. (No model.)

To all whom it may concern:

Be it known that I, CHARLES WAGNER, a citizen of the United States, and a resident of the city of New York, borough of Manhattan, in the county and State of New York, have invented a new and Improved Machine for Covering Lithographic-Printing Rollers, of which the following is a full, clear, and exact description.

10 The invention relates to the manufacture of printing-rollers for lithographic-printing machines; and its object is to provide a new and improved machine for drawing the leather, skin, or cover over the filling in a very simple, quick, and effective manner without requiring skilled labor.

15 The invention consists of novel features and parts and combinations of the same, as will be more fully described hereinafter and then 20 pointed out in the claims.

25 A practical embodiment of the invention is represented in the accompanying drawings, forming a part of this specification, in which similar characters of reference indicate corresponding parts in all the views.

30 Figure 1 is a side elevation of the improvement. Fig. 2 is a front view of the same. Fig. 3 is a plan view of the upper end of the machine. Fig. 4 is a sectional plan view of the improvement on the line 4-4 of Fig. 2, and Fig. 5 is a transverse section of the same on the line 5-5 of Fig. 2.

35 The improved machine is mounted on a base A, carrying a number of spaced columns B, connected with each other at their upper ends by a cross-plate B', and on the said base A is secured an upwardly-extending socket C, in which is fastened the lower end of a stock D, carrying the usual filling D', over which 40 leather, skin, or a cover D² is to be drawn to complete the lithographic-printing roller, as hereinafter more fully described.

45 A set-screw C' serves to fasten the stock D in the socket C. The upper end of the skin or cover D² is engaged by a hook E, held on one end of a rope E', extending upwardly over an overhead pulley E², journaled in suitable bearings on a rod E³, held vertically 50 slidable in the cross-plate B' and adapted to be secured therein by a set-screw E⁴. (See Fig. 3.) The downwardly-extending end of

the rope E' is provided with a weight E⁵ to counterbalance the weight of the skin D².

The lower end of the skin D² is engaged on opposite sides by clamps or gripping-jaws F, held on cables G, winding on grooved drums H, secured on a shaft I, journaled in suitable bearings A', secured on the base A. On one end of the shaft I is secured a ratchet-wheel J, engaged by a pawl J', fulcrumed on a foot-lever J², hung loosely on the shaft I and normally held in an uppermost position by a spring J³, a stop-pin J⁴ limiting the upward movement of the said foot-lever or treadle, as illustrated in Figs. 1 and 2. The stop-pin J⁴ is held vertically adjustable on one of the columns B. Now by the operator pressing the foot-lever J² the pawl J' imparts a rotary motion to the ratchet-wheel J, so that the latter turns the shaft I and drums H to wind up the cables G, and thereby cause the clamps F to pull on the skin D² in a downward direction to draw the skin over the filling D'. When the operator releases the pressure on the foot-lever or treadle J², then the spring J³ returns the foot-lever to an uppermost position and the pawl J' glides during this upward movement of the lever back over the teeth of the ratchet-wheel J, and the latter is held against return movement by a dog J⁵, fulcrumed on the base A.

In order to insure a proper winding and unwinding of the cables G on the drums H, I engage each of the cables directly opposite the corresponding drum with a grooved pulley K, mounted to rotate and to slide longitudinally on a rod K', fastened in an arm L by a set-screw L', the said arm L being fulcrumed at its lower end at L² on the base portion of the socket C, and the upper end of the said arm L is engaged by an adjusting-screw L³, screwing in the socket C. By turning the screw L³ the arm L may be swung inward or outward, so as to move the rod K' transversely to bring the grooved pulleys K in proper relation to the cables G and the drums H, so that when the cables wind up on the drums the pulleys K cause the cables G to follow the spiral grooves of the pulleys K, and consequently the convolutions of the cables do not double up, but range one alongside the other to insure a uniform winding

up of the cables G to exert an equal downward pull by the clamps F on the skin D² to draw the same in perfect order over the filling D'. As the skin D² fits very closely onto the filling D', it is absolutely necessary that an equal pull be exerted on both sides of the lower end of the skin D² to insure the proper formation of a lithographic-printing roller, and this is accomplished by the arrangement

10 above described.

In using the machine the stock D, with the filling D' thereon, is inserted into the socket C and fastened therein by the set-screw C', and the upper end of the skin D² is engaged 15 by the hook E, and the skin is drawn upward by the counterweight E⁵ on the rope E' until the lower end of the said skin is above the top of the stock D. The operator next swings the dog J⁵ and pawl J' out of mesh with the 20 ratchet-wheel J and then pulls on the cables H, so as to unwind the same on the drums H to permit of connecting the clamps or jaws F with the lower end of the skin D² at opposite sides thereof. The skin D² extends in 25 axial alinement with the stock D and its filling D', and when the pawl J' and the dog J⁵ are thrown in mesh with the ratchet-wheel J and the foot-lever or treadle J² is alternately pressed and released then an intermittent 30 winding up of the cables G on the drums H takes place to cause the clamps F to draw the skin D² downward over the filling D', as before explained. When the skin is in position on the filling D', then the clamps F are 35 disconnected and the hook E is unhooked, after which the printing-roller is removed from the socket C.

The cross-plate B' is preferably provided at its front with a movable section B², hinged 40 at B⁸ to the plate and adapted to be locked in position on the plate by a screw B⁴ on the free end of the section B². By this arrangement the section B² may be swung outward to give convenient access to the central opening in the plate B' for the insertion of the stock D in the socket C in case very long 45 printing-rollers are covered with correspondingly long skins in the manner described. On the columns B are adjustably held steps 50 B⁵ B⁶ for the operator to step on when attaching the hooks E to very long skins D².

Having thus described my invention, I claim as new and desire to secure by Letters Patent—

55 1. A machine for placing skin on the filling of a printing-roller, consisting of a movable suspension device for supporting the skin above the roller, a device for engaging the end of the skin, and means for drawing the same 60 in the direction of the length of the roller and over the filling thereof, as set forth.

2. A machine for drawing skin in position on lithographic-printing rollers, consisting of a counterbalanced suspension device for engaging the upper end of the skin, and a drawing device for engaging the lower end of the

skin, to draw the latter lengthwise over the filling of the roller, as set forth.

3. A machine for placing skin on a printing-roller, consisting of a drawing device having 70 clamps for directly engaging opposite sides of the skin at one end, and means for moving the clamps lengthwise of the roller, to draw the skin over the filling of the roller, as set forth. 75

4. A machine for placing skin on a printing-roller, consisting of a drawing device having 80 clamps for directly engaging opposite sides of the skin at one end thereof, and a manually-controlled means for intermittently moving the clamps lengthwise of the roller, to draw the skin over the filling of the roller, as set forth.

5. A machine for placing skin on a printing-roller, comprising clamps for directly engaging 85 opposite sides of the skin at one end thereof, cables each carrying a clamp, grooved drums on which wind the said cables, and means for rotating the said drums, as set forth. 90

6. A machine for placing skin on a printing-roller, comprising clamps for engaging opposite sides of the skin at one end thereof, cables carrying the said clamps, grooved drums on which wind the said cables, means for rotating the said drums, and grooved guide-pulleys engaging the said cables opposite the 95 drums, the guide-pulleys being mounted to turn and to slide in the direction of the length of the drums, as set forth. 100

7. A machine for placing skin on a printing-roller, comprising clamps for engaging opposite sides of the skin at one end thereof, cables carrying the said clamps, grooved drums on which wind the said cables, means for rotating the said drums, grooved guide-pulleys 105 engaging the said cables opposite the drums, the guide-pulleys being mounted to turn and to slide in the direction of the length of the drums, a carrier for the said guide-pulleys 110 to slide and rotate on, and means for adjusting the said carrier, as set forth.

8. A machine for placing skin on a printing-roller, comprising clamps for engaging opposite sides of the skin at one end thereof, cables carrying the said clamps, grooved drums on which wind the said cables, means for rotating the said drums, grooved guide-pulleys 115 engaging the said cables opposite the drums, the guide-pulleys being mounted to turn and to slide in the direction of the length of the drums, a carrier for the said guide-pulleys 120 to slide and rotate on, and means for adjusting the said carrier, the carrier comprising an arm mounted to swing, means for adjusting the arm and locking it in position and a rod carried by the arm, on which the pulleys 125 are mounted to slide and turn, as set forth.

9. A machine for placing a cover on a roller, comprising a movable supporting device for 130 the cover, cables each provided with means at one end for directly engaging one end of the

cover, drums upon which the cables wind, and means for operating said drums, as set forth.

10. A machine for placing a cover on a roller, comprising a movable supporting device for the cover, cables provided with means at one end for engaging one end of the cover, drums upon which the cables wind, traveling guides for the said cables, and means for operating the drums, as set forth.

11. A machine for placing a cover on a roller, comprising a counterbalanced suspension device for engaging one end of the cover to support it above the roller, cables provided

with clamps at one end for engaging the other end of the cover at opposite sides thereof, drums upon which the cables wind, means for guiding the cables to and from the drums to permit of the proper winding and unwinding of the same, and means for operating said drums, as set forth.

In testimony whereof I have signed my name to this specification in the presence of two subscribing witnesses.
